Primary Examiner — Catherine A Tuttle(74) *Attorney, Agent, or Firm* — Stephen J. Weyer, Esq.; Stites & Harbison, PLLC(57) **CLAIM**

The ornamental design for a rattle, as shown and described.

DESCRIPTION

FIG. 1 is a top, front and left side perspective view of the rattle embodying our design.

FIG. 2 is a left side view thereof.

FIG. 3 is a right side thereof.

FIG. 4 is a front elevation view thereof.

FIG. 5 is a rear view thereof.

FIG. 6 is a top plan view thereof; and,

FIG. 7 is a bottom plan view thereof.

The dotted lines in FIG. 3 represent a feature of the rattle that forms no part of the claimed design.

1 Claim, 7 Drawing Sheets(56)
